UNITED STATES PATENT OFFICE.

GEORGES VALENSI, OF PARIS, FRANCE.

RECEIVING DEVICE FOR DISTANT-VISION INSTALLATION.

Application filed September 7, 1928, Serial No. 661,507, and in France December 29, 1922.

The present invention relates to improvements in receiving devices for distant vision installations, that is devices adapted to reproduce in half-tones, in lines, or in any other structure, with or without colours and relief, the image of stationary or moving objects explored at a remote transmitting station.

The installation is of the general type wherein the object whose image is to be transmitted is explored, point by point, at the transmitting station, the light of the successive points thus explored acting upon a photo-electric cell which controls a photo-electric current. The latter is transmitted by wire or wireless transmission to the receiving station where the image is to be reproduced. For this purpose the photo-electric current produces at the receiving station, in a manner to be later described, a luminous point of variable brilliancy moving at a sufficient speed to provide for the persistence of the luminous impressions. The exploration at the transmitting station and the reproduction of the image at the receiving station are synchronized by a synchronizing current transmitted by wire or wireless transmission. In the case of colour and or relief reproductions, the image to be transmitted is decomposed into several elementary images by means of colour screens and or a stereoscopic device, said elementary images being separately and synchronously explored so as to act upon a corresponding number of photo-electric cells. Each elementary image is transmitted and reproduced in the manner above indicated and the various images thus reproduced are recombined into the final image in colour and or relief by means of coloured screens and or a stereoscopic device.

One object of the invention consists in providing a receiving plant adapted to afford a very true reproduction of the images transmitted from the remote transmitting station, said images being however very sharp and luminous, so as to be visible, if desired for many persons at the same time. For this purpose, the photo-electric current, which only possesses a small energy, is adapted to modulate electric or electromagnetic rays produced by a local source of energy, which may be as strong as desired.

With the same object in view, the invention also consists in providing at the receiving station a luminous wide spot of uniform or substantially uniform brightness over its whole surface, the intensity of the illumination varying in accordance with the fluctuations of the photo-electric current, and in exploring such luminous wide spot, point by point, synchronously with the exploration at the transmitting station. The exploration of the object at the transmitting station and the exploration of the luminous wide spot at the receiving station may thus take place with identical exploring devices, which may be readily synchronized, thus affording a very accurate reproduction.

In order to increase the accuracy of the reproduction, my invention has also for its object to provide improved exploring means adapted to afford an exploration in a continuous path, whereby a temporary and short lack of synchronism between the exploring devices at the transmitting and receiving stations will not have a so much detrimental effect than heretofore, said exploring means being further adapted to afford an exploration at a uniform speed, so as to accurately reproduce, in the whole image, the tones and general appearance of the object whose image is transmitted. According to my invention, said exploring means embody preferably rotating opaque discs having transparent lines formed with portions of special spiral, affording the continuous exploration at uniform speed.

In order to provide for a powerful illumination, and a great sensitiveness, my invention further consists in generating electric rays in a tube containing a suitable gaseous material becoming illuminated when an electric current passes through the same. The discharge is produced between the electrodes of the tube to which is applied the photo-electric tension, suitably amplified, in an amplifier fed by the local source of energy. The amplifier may be combined with the illuminating tube and in this latter case, the discharge is produced by the current of the local source of energy and is controlled by modulating electrodes to which the photo-electric tension is applied.

A further object of the invention consists in providing means for facilitating the elec-

tric discharge in devices embodying discharge tubes, so as to reduce as far as possible the priming potential.

The invention will be clearly understood with reference to the appended drawing which shows, by way of example, a number of embodiments of the invention, and in which:

Fig. 1 shows in a diagrammatical manner 10 a complete installation for distant vision, according to the invention.

Fig. 2 is an elevational view of one embodiment of my exploring means.

Fig. 3 is a diagram illustrating another 15 embodiment of the exploring means.

Fig. 4 is a diagram of the spiral transparent lines provided on the exploring members.

Fig. 5 shows at an amplified scale the path 20 of exploration of an image.

Fig. 6 is a diagrammatical sectional view of a receiving plant, according to a modification.

Fig. 7 is a diagrammatical sectional view 25 of a receiving plant, according to a further modification.

Referring to Fig. 1, A denotes the transmitting station and B the remote receiving station. 101 is the object whose image is 30 to be transmitted from station A to station B; said object is disposed in a chamber 102 and is strongly illuminated by lighting projectors 203 associated with condensers 204. The image of object 101, given by the objective lens 103, is explored by exploring means 35 embodying two rotating discs 104 and 105, to be later described, and is formed preferably in the plane between said rotating discs. Said discs mask the whole image of the object, except one point, which is moved in a 40 continuous path and at a uniform speed. The small pencil of light which is allowed to pass beyond discs 104, 105 is directed through a collimator 108 over a photo-electric cell, for instance a potassium cell 109, 45 contained in a metallic box 110 forming an electrostatic screen. The electrode of potassium 112 and the anode 111 are suitably connected to an amplifier 114, for example a three electrode lamp, fed by an electrical 50 source 115 through a resistance 116 in series with the amplifier plate. A battery 113 connected to electrode 112 (of 100 volts about) produces the photoelectric current. 117 denotes a protecting resistance. The variations 55 in the intensity of the light acting upon the photo-electric cell produce corresponding variations in the photo-electric current, amplified by lamp 114, and the terminals 120 and 121 of the transmitting station have a corresponding varying potential difference.

The transmitting station further comprises a multipolar continuous current motor 106 fed by an electrical source 107. Disc 60 105 is keyed to the motor shaft to which is

also secured a gear wheel 205 meshing with a gear wheel 206 keyed to the shaft 207 of disc 104. Rotation of motor 106 imparts rotation in contrary directions to discs 104, 105. Motor 104 has an even number $2p$ of poles and two points of the armature, spaced through $\frac{2\pi}{2p}$ are connected to the respective rings 136, 137 whose brushes are connected to terminals 208, 209. Due to the special connection of rings 136, 137, with the armature, motor 106 operates as a small mono-phase commutating machine and is adapted for synchronizing purposes, as will be hereinafter described.

Terminals 120, 121 of the photo-electric circuit are connected by a wire or wireless transmission to terminals 129, 130 of an amplifier 210 comprising several amplifying lamps 211 with the usual associated organs and by means of which the photo-electric current is suitably amplified. The amplified photo-electric current is supplied through leads 200, 201 to the modulating electrodes of an electric rays tube 122.

Tube 122 is filled with a gaseous material and comprises a filament 124 heated by a battery 127 and an anode 126, which is under the tension of a local source of additional energy 128 of any suitable kind. The intermittent luminescence of the gaseous material, produced by the discharge between filament 124 and anode 126, is modulated by the photo-electric tension applied to the filament 124 and to an electrode 125 interposed between filament 124 and anode 126 and produces a luminous wide spot of light of variable light intensity.

The luminous wide spot produced by tube 122 is explored, point by point, according to the same continuous path and at the same uniform speed as the exploration at the transmitting station, by means of two discs 134, 135, similar to discs 104, 105. Disc 135 is keyed to the shaft of a motor 106^a identical with motor 106 and provided, as before, with a feeding source 107^a and rings 136^a, 137^a, connected to terminals 208^a, 209^a. Disc 134 is keyed to a countershaft 207^a driven by gear wheels 205^a, 206^a.

The synchronism in the rotation of the exploring means at both stations, that is the synchronism between motors 106 and 106^a is obtained by the Poirson's arrangement, used in secret telephony. For this purpose the terminals 208, 209 are connected by a wire or wireless transmission to the terminals 208, 209.

The two motors will operate as an alternator and synchronous motor unit, coupled at the said speed and phase; means may be provided whereby the two motors will be in constant mutual reaction and will act alternately as driven synchronous motors, (which will require a reversible wire or wireless

connection), or else a given motor shall be always driven by the other, so that a non-reversible connection can be used. It is preferable to provide each motor with a suitable speed regulator of a known type.

It will be understood that the luminous point visible to the eye located at 132 is moving according to the same path and at the same speed as the luminous point corresponding to the intersecting point of the transparent lines of discs 104, 105; the speed of displacement being sufficient to secure the persistency of the luminous impressions on the retina, the image of the object 101 will 10 be finally reproduced at the receiving station.

It will be seen that, due to the amplification, by means of amplifier 210 and the provision of a local source of additional energy 20 128, the energy of the photo-electric current flowing between terminals 120, 121, 129, 130, may be reduced to a minimum, that is to the order of magnitude of ordinary telegraphic or telephonic currents usually transmitted 25 by lines or radio links, while the illumination of tube 122 is however sufficiently powerful to afford a bright and sharp image.

In order to secure an exploration at uniform speed and according to a continuous path I prefer to provide exploring means 30 consisting of two discs 134, 135 (Fig. 2) of opaque material but having transparent lines adapted to cross each other at a point moving along a zigzag continuous path a , 35 a^1, a^2, a^3 , etc., such as illustrated in Fig. 5, and at a uniform speed. For this purpose, disc 135 is provided with a transparent line 212 made of two spiral arcs and disc 134 with a series of portions of spiral $e f, f e_1$, 40 $e_1 f_1, f_1 e_2$, etc., of contrary directions. The shape of these spirals is shown at a larger scale in Fig. 4 and is analytically defined by the equation:

$$\rho = a + b \sin \theta$$

45 where ρ and θ are the polar coordinates relatively to the centre of the disc and a, b suitable constants.

The first disc has for instance a transparent line with 100 teeth of such outline whilst the second has a transparent slot made of two spiral arcs of the same radial height as the spiral teeth. The two discs have the same diameter and are disposed in parallel 50 and closely adjacent places in an orthogonal disposition; they are rotated about their axes at the same speed but in opposite directions. The intersecting point of their transparent lines will move over the square $a b c d$ according to the path indicated in Fig. 5, 55 in front of the luminous spot of variable brilliancy.

It is evident that instead of using a screen having 100 teeth and rotated in the direction 60 contrary to the other disc at 8 or more revolu-

tions per second, I may use a screen with 10 teeth rotated at 80 revolutions per second, the other screen still rotating in the opposite direction at 8 revolutions per second.

It is evident also that other arrangements 70 of discs such as 134 and 135, provided with such spiral arcs might be used in order to provide an exploration at a uniform speed according to the continuous path indicated in Fig. 5.

Similar movable screens will obviously be used for the exploration of the image to be transmitted and the reproduction of the same at the receiving station.

The same movable screens can also be 80 used in the case of colour or relief reproduction, all being operated by the same power shaft; the two power shafts of the two corresponding stations are maintained in exact synchronism as concerns speed and phase 85 due to the motors 106, 106^a connected in the manner above indicated.

The exploring means may also consist of paper bands or photographic films provided 90 with transparent broken lines upon an opaque background, corresponding to the lines shown in black upon a white background in Fig. 3. The first line may consist of 200 rectilinear elements inclined alternately at 45° in either direction, so as to 95 form 100 teeth whose width is double the height. The second line is formed by a single tooth which has the same height as the preceding teeth but whose length is 100 times greater. These opaque bands thus 100 provided with transparent lines are moved at constant speed at right angle to each other.

The modulation of the rays produced by the local source of energy may be effected by 105 other means than those above indicated. In the case of electromagnetic rays, the modulation may be obtained by the electromagnetic action of coils or condensers, to which the photo electric tension is applied. In the 110 case of electric rays, the modulation is obtained by the control of the number, the speed or the path of the electric particles, according to the nature and disposition of the rays generating electrodes and modulating electrodes.

The invention also contemplates the use 115 of devices in which a liquid or gaseous luminescent substance is contained in a tube which is fitted as an electric rays generator, but in which said liquid or gas is separated from the rays producer by a thin wall permeable only to electrified particles.

However, I prefer to separate the receiver 120 into two different tubes or sets of tubes, as explained with reference to Fig. 1. In the first set of tubes which forms an ionic or electronic relay (amplifier 210), the electric rays produced by a local source of energy are modulated according to the varia- 125 130

tions of the photo-electric current from the transmitting station, and hence there will be produced an alternating or undulating tension of considerable amplitude, e. g. several tens or even several hundreds or several thousands volts. The second tube 122 which constitutes a luminescent tube, will then only contain two electrodes 124, 125 and a suitable gaseous atmosphere (neon, 10 helium, argon, mercury vapor, etc.) or a suitable liquid which will become illuminated when an electric current passes therethrough. The alternating or undulatory tension produced by the first set of tubes is applied to the electrodes of the luminescent tube, and in the latter I obtain a wide spot of light whose geometrical position and form are invariable, but whose brilliancy will vary according to the fluctuations of 15 the tension employed, that is, according to the fluctuations of the received photo-electric current, as above explained.

In other words the electrode 126 and the electrical sources 127 and 128 may be dispensed with. In such cases, the amplified photo-electric tension which is directly applied to electrodes 124, 126 produces by itself the electric discharge; the local source of additional energy herein consists of the 20 sources of current feeding amplifier 210. Alternatively, amplifier 210 may be dispensed with, and, in such case, the local source of additional energy is constituted only by the electrical source 128.

In practice, it is found necessary that the 25 alternating or undulatory tension prevailing between the electrodes of the luminescent tube should have an amplitude which is distinctly greater or less than the priming potential in the case of a luminescent tube, (or in the case of a tube containing a luminescent liquid, the pseudo-counter E. M. F. which prevails between these electrodes). It is therefore required, in order to avoid excessive amplification of the received photo-electric current, to reduce the priming potential of the luminescent tube as much as possible. For this purpose, I may employ 30 tubes containing neon, helium or argon (or a suitable mixture of the three) and provided with suitable electrodes covered for instance with sodium or potassium. If desired, the electrodes can be illuminated by ultra-violet light, so that they will produce a photo-electric disengagement of electrons 35 and thus facilitate the discharge. The electrode may also consist of a hot filament placed in front of the anode, as in the Tungar rectifying tubes, so as to make use of a thermionic discharge of electrons. Use can be made also, at the bottom of the luminescent tube and adjacent one of the electrodes, of an auxiliary continuous current arc in order to maintain the atmosphere in a 40 slightly ionized condition and to facilitate

the discharge between the two main electrodes.

Obviously, the transformation into luminous energy of the energy of the electric rays produced by the local source of energy 45 may be obtained in a manner different from that above indicated and, namely, the luminescent gas may be replaced by a luminescent liquid or even by a screen of fluorescent solid material. A device embodying such a solid 50 screen is shown in Fig. 6.

Cathodic rays are generated in a tube 40 and modulated by a grid 45 located between the cathode filament 41 and the perforated anode 43 and as near said filament as possible, for instance at a distance of $\frac{1}{10}$ of a millimeter. The filament is constituted by a plane loop or by one or several rectilinear threads, tensioned in the same plane and mounted in parallel, and is heated by a 55 source of energy for instance a battery 42. The different portions of the filament are disposed below the solid parts of the grid, the latter being made of a perforated disc with numerous small aligned holes, in order 60 to be protected against the impact of the positive ions which are directed towards the cathode through the holes of the grid. A screen 50 connected to the negative end 65 of the filament, collects said positive ions and at the same time limits their path, and consequently reduces the ionization of the 70 gas in the neighborhood of the electrodes.

A battery 46 maintains the grid 45 constantly negative with regard to the filament, which affords the omission of a protecting screen beyond said filament, and hence to 75 reduce to a minimum the distance between the grid and the filament. This results in the possibility of modulating the rays by the 80 use of an extremely small energy, for instance less than 1 microampere under a variation of tension of the grid of about 10 85 volts. A potentiometer 47 is mounted in series with or in opposition to the battery 90 46, and receives at its terminals 48 and 49, the photo-electric current proceeding from the transmitting post. The electrons emitted by the filament 41 are set in motion by the 95 perforated anode 43 in the circuit of the 100 source of electrical energy 44 and thus brought for instance to a potential of several hundreds of volts with respect to the filament. These electrons pass through the 105 perforated anode 43 and form a divergent 110 pencil which, due to the suitable shapes and relative positions of the filament 41, grid 45 and anode 43, produces upon the fluorescent screen 52 fixed on the wall of tube 51, a wide luminous spot, whose surface is for 115 instance of several square centimeters, and having a uniform brilliancy over its whole 120 surface. This brilliancy is variable according to the potential of the grid with respect 125 to the filament, i. e. according to the photo- 130

electric current proceeding from the transmitting station. Said luminous spot of variable brilliancy is observed through the exploring screens 53, 54.

The small tube 40 containing the filament and its screen, and the modulating grid may serve as a support for the anode. Said tube is located within the long tube 51 carrying the fluorescent screen 52.

10 Although I prefer to explore the luminous wide spot constituted by the luminescent material by means of the discs of Fig. 2, I may however perform the exploration by other means provided that said means afford 70
15 an exploration at a uniform speed and according to a continuous path. For instance, I may produce with the luminous wide spot a fixed luminous point and I then displace the image of said point in a continuous 80
20 manner and at a uniform speed by optical means operated electrically or mechanically. Said optical means (Fig. 7) consist of two mirrors 31, 32 (or two prisms, or the like) which are movable about suitable axes and 85
25 are actuated by electrical or mechanical devices, or by like means. These mirrors may be mounted upon oscillographs or galvanometers supplied by alternators or generators of any kind producing an alternating 90
30 E. M. F. and driven or controlled by the motor 106^a of the station and whose E. M. F. has the form of a wave corresponding to the path of exploration chosen for the original image. The mirrors can 95
35 also be mechanically operated by the power shaft for instance by means of cams whose profile is also made to correspond to the chosen path of exploration; the electric control and the mechanical control may also be 100
40 used in combination.

This arrangement may be associated for example with a tube 26 provided with a solid fluorescent screen 25 which is illuminated by a pencil of electric rays of short length. A 105
45 tube of this kind is advantageously provided with suitable means adapted to discharge the fluorescent substance and the walls, and to cause the negative charges to return to the anode. For this purpose the tube may contain a small amount of an ionized neutral gas, the electrodes 21, 23 which produce the electric rays (e. g. Wenhelt cathode and perforated anode) being disposed if desired in a very small inner tube 20 so 110
50 as to separate them from the gas contained in the main tube 26. Tube 20 thus constitutes a small cathode rays tube comprising an oxide-covered filament 21 (which can be protected by the screen 22), and the perforated anode 23. The cathodic rays produced by the local source of additional energy 128 and modulated by the modulating electrode or electrodes 24 according to the fluctuations of the photoelectric current applied to terminals 200 and 201, will produce 115
55

on the fluorescent screen 25, at the end of the outer tube 26, a luminous wide spot of variable brilliancy. An opaque screen 27 having a hole 28 can be used to suitably limit the outline of this spot. It is obvious 75
70 that I may use all methods of modulation, and that the modulating electrode or electrodes may occupy any desired position in the tubes 20 or 26.

The optical arrangement preferably contained in a camera 29, displaces the image of the luminous spot of variable brilliancy appearing through 28 in exact synchronism with the exploration of the original image. For this purpose the mirror 32 is attached 80
85 to an oscillograph diagrammatically illustrated by the coil 30 and the larger mirror 31 is actuated by a cam 33. Mirrors 31 and 32 are respectively oscillated about an axis perpendicular to the plane of the figure and about an axis parallel with the plane of the figure. The galvanometer or oscillograph controlling the mirror 32 is supplied by a current having a frequency of about 800 periods and whose wave-form (corresponding to the chosen path of exploration) has for instance the shape of a series of isosceles triangles, assuming that the exploring path is a sinuous line similar to that shown in Fig. 5. The outline of cam 33, which also 90
95 corresponds to the exploration path, consists of an indented cylindrical surface whose generatrix is formed by spiral lines similar to those shown in Fig. 4 that is whose equation in polar co-ordinates ρ θ has the linear form $\rho = a\theta + b$. The alternator (not shown) supplying the galvanometer 30 and the shaft of cam 33 are driven by the main motor 106^a of the station. The condenser 34 and objective 35 deflect the light pencil towards the 100
105 eye placed at 36, where the light pencil gives a moving image of hole 28.

In all the devices above described, the eye may obviously be replaced by a photographic surface such as a sensitive plate or 110
115 a film in the case of tele-cinematography. In the case of colour reproduction, the elementary monochromatic images may be obtained, as above indicated, by means of colour filters. However, use may also be made of luminescent or fluorescent substances having respectively different colors.

Finally, the receiving plant may be combined with a transmitting plant. In this case, motor 106 of the transmitting plant 120
125 will be also motor 106^a of the receiving plant, while the remote station will also have a single motor 106, with both functions.

Having now described my invention, I declare that what I claim as new and desire to secure by Letters Patent is:

1. In a distant vision installation comprising a photo-electric cell at the transmitting station and an electric device at the receiving station, 130

- ceiving station adapted to be acted upon by the photo-electric current proceeding from said photo-electric cell, a local source of additional energy for producing rays in said 5 electric device, means in the path of said rays for producing a luminous wide spot, means for acting upon said rays in accordance with the variations of the photo-electric current, means for producing a luminous point from said luminous wide spot and for displacing said point in a continuous manner and at a uniform speed, and means for synchronizing said exploration with the exploration at the transmitting station 10 of the image to be reproduced.
2. A distant vision installation comprising a photo-electric cell for the transmission and a receiving electric device giving a fixed luminous wide spot, means for varying the 15 intensity of said luminous wide spot in accordance with the variations of the photo-electric current proceeding from said photo-electric cell, exploring means embodying two opaque adjacent discs of the same radius disposed above said fixed luminous wide spot and adapted to rotate at great speed, each of said discs being provided with a transparent line formed with portions of special spiral, the equation of said special 20 spiral in polar coordinates ρ θ related to the center of said disc being of the linear form $\rho = a + b\theta$, and a motor rotating said discs in synchronism with the corresponding motor at the distant installation.
3. A distant vision installation comprising a photo-electric cell at the transmitting station, the combination at the receiving station of a tube containing a gaseous material becoming illuminated when an electric current 25 passes through the same, electric means for producing an electric discharge in said tube, means for amplifying the photo-electric current proceeding from the photo-electric cell, groups of electrodes within said 30 tube and to which the amplified alternating
- tension is applied, means for exploring point by point the source of light constituted by said tube, and means for synchronizing such exploration with the exploration point by point at the transmitting station of the image to be reproduced.
4. A distant vision installation comprising a photo-electric cell at the transmitting station, the combination at the receiving station of a tube containing a gaseous material 35 becoming illuminated when an electric current passes through the same, electric means for producing an electric discharge in said tube, means for amplifying the photo-electric current proceeding from the photo-electric cell, groups of electrodes within said tube and to which the amplified alternating 40 tension is applied, means associated with said groups of electrodes and adapted to produce an auxiliary emission facilitating said electric discharge, means for exploring point by point the source of light constituted by said tube, and means for synchronizing such exploration with the exploration point by point at the transmitting station of the image to be reproduced.
5. A distant vision installation comprising a photo-electric cell at the transmitting station, the combination at the receiving station of an electric rays tube filled with 45 a luminescent gaseous material, a local source of additional energy feeding said electric rays tube, means for modulating said electric rays in accordance with the variations of the photo-electric current proceeding from the photo-electric cell, means for exploring point by point the source of light constituted by the intermittent luminescence of said gaseous material and means 50 for synchronizing such exploration with the exploration point by point at the transmitting station of the image to be reproduced.
- In testimony whereof I have signed my name to this specification.

GEORGES VALENSI.
